ATTORNEYS.

UNITED STATES PATENT OFFICE

ROBERT SAA, OF AUBURN, CALIFORNIA

ADJUSTABLE SHADE ROLLER MOUNTING

Application filed March 2, 1932. Serial No. 596,315.

My invention relates to improvements in adjustable shade roller mountings, and it consists of the combinations, constructions and arrangements hereinafter described and claimed.

An object of my invention is to provide an improvement over the form of the device shown in my co-pending application, Serial No. 563,197, filed September 16, 1931. In said application, I showed identical gripping means for adjustably holding a shade roller in any desired position on the window and for adjustably holding the bottom of the shade. I further showed common guides for the shade roller and for the shade and disclosed brackets for supporting the shade roller, these brackets being held against swinging motion by having lugs that are slidably received in the guides.

The principal object of the present invention is to simplify the mechanism shown in my co-pending application and to provide a different type of gripping shoe. These improvements will be set forth in the body of the specification.

Other objects and advantages will appear in the following specification, and the novel features of the device will be particularly pointed out in the appended claims.

My invention is illustrated in the accompanying drawing forming a part of this application, in which

Figure 1 is a front elevation of the device;

Figure 2 is an enlarged detail of a part of the device, a portion being shown in section;

Figure 3 is an enlarged detail section taken along the line 3—3 of Figure 1;

Figure 4 is a perspective view of a guide-gripping shoe;

Figure 5 is a view similar to Figure 3, but shows a modified guide-gripping member; and

Figure 6 is a view similar to Figure 2, but shows the modified member.

In carrying out my invention, I make use of a window frame, indicated generally at 1, and this frame is provided with the usual sliding sashes 2. Guides 3 are disposed at the sides of the window frame, and it will be noted from Figure 3 that each guide is pro-

vided with a wood runner 4 to which a metal strip 5 is secured by rivets 6, or other suitable fastening means. The strip 5 has openings 7 therein for receiving nails 8, and these nails are driven into the frame 1 and thus secure 55 the guide 3 in place.

Figure 3 also shows the strip 5 as being bent in a S-shape in cross section so as to provide two guide channels 9 and 10. The guide channel 9 faces toward the wood runner 4, 60 while the guide channel 10 faces in the opposite direction.

I now provide two tubular members 11 and 12 which are slightly flattened and which are identical in construction. The member 11 supports a shade roller 13, while the member 12 is secured to the bottom of the shade 14. Since both members 11 and 12 are identical in construction, the description of one will suffice. 70

In Figures 2 and 3 I show an enlarged detail view of a portion of the member 12. It will be noted that this member extends entirely across the bottom of the shade 14 and that the ends of the member house casings 15, which in turn carry guide-gripping mechanisms. A casing 15 is disposed at each end of the member 12 and also at each end of the member 11. Within the casing, I pivotally mount a cam 16, the cam being pivoted at 17 to the casing 15 and having a cam-gripping edge 18. The pin 17 is received in a slot 17' in the cam 16. A spring 19 tends to swing the cam in a counter-clockwise direction for causing the cam-gripping edge 18 to bear 85 against the bottom of the channel 10.

A guide-gripping shoe 19, of the shape shown in Figure 4, is U-shaped in cross section so as to slidably engage with the guide 3, and has inwardly-extending tongues 20, 90 which are slidably received in the channel 10.

The side 21 of the shoe 19 is slidably received in the channel 9. The shoe 19 has an ear 22, and the cam 16 is pivoted to the ear at 23. 95

It will be noted from this construction that the member 12 may be manually grasped and moved downwardly, and during this movement, the cam-gripping edge 18 will slide 100 freely along the bottom of the channel 10 and

the shoe 19 will slide along the guide 3. The spring shade roller 13 tends to wind the shade around the roller, and as soon as the member 12 is freed, the spring roller will tend to move 5 the member upwardly. This is prevented by the spring 19 swinging the cam 16 in a counter-clockwise direction so that the cam edge 18 and the shoe 19 will grip the guide 3 and hold the member 12 in adjusted position.

10 The identical gripping means is used in the member 11, except that the gripping means are reversed and the cams 16 are swung into gripping engagement and tend to prevent the member 11 from moving downwardly. Referring briefly to the member 11, it will be noted that the cams 16 are connected to a disk 24 by cords 25 that are passed over idlers 26 in the manner shown. The tube 11 has an opening 27 in its top, and the cords 25 pass 20 through this opening and are secured to the disk 24. A lifting cord 28 is secured to the member 11 and passes entirely through the disk 24 and is provided with a tassel 29. In lifting the member 11, the tassel 29 is grasped 25 and manually raised and this will move the member 11 upwardly and the cams 16 and the shoes 19 will permit this movement.

The member 11 carries shade roller hangers 30, which in turn carry the shade roller 13. 30 The hangers 30 have wings 31 that are slidably received in the channels 10 of the guides 3. It will therefore be seen that an upward movement of the member 11 will raise the shade roller 13.

35 When the operator wishes to lower the member 11, he grasps a disk 24 and moves it toward the tassel 29. Of course, during this movement, the cords 25 and 28 extend vertically above the member 11. The movement of 40 the disk 24 with respect to the guide cord 28 holds the strings 25 and frees the cams 16 and this permits the member 11 and the shade 13 to move downwardly. When the desired position is reached, the disk 24 is freed and 45 the cams 16 and the shoes 19 will hold the shade roller in a desired position.

Since the shade roller 13 is of the spring type, it will have a tendency to wind the shade 14 thereon at all times. In order to hold the 50 shade in any desired position, I provide the member 12 with the cams 16 and shoes 19, and this member will engage with the guides 3 in the same manner as the guide-gripping means in the member 11. In lowering the 55 shade 14, the tassel 29 of the member 12 is grasped, and since this tassel is connected directly to the member 12 by the cord 28, it will lower the member 12. When the operator wishes to raise the shade 14, he grasps the disk 60 24 of the member 12 and a downward movement will free the cams 16 and the shoes 19 so that the shade may be wound upon the roller 13. The cord 28 acts as a guide for the disk 24, and the tassel 29 limits the movement of 65 the disk on the cord.

In my co-pending application, I showed the rollers 26, disposed adjacent to the cams 16, as being carried by a separate member which was inserted into the tube. In the present instance, I show the rollers 26 as being 70 carried by the casing 15. Furthermore, in the co-pending application, I showed the center rollers 26 as being carried by a separate insertable member, but in the present case, I show these rollers as being carried directly 75 by the tubes 11 and 12.

In this way, I omit two roller-carrying members and thus simplify the number of parts.

The gripping shoe 19, shown in this case, 80 is not disclosed in the co-pending application. It will further be noted that the shape of the guide 3 differs from that shown in the co-pending application. The wings 31 on the hangers 30 slide in the channels 10 85 instead of abutting against a shoulder, as is disclosed in the co-pending case. The wings are therefore prevented from swinging in either direction.

In Figures 5 and 6 I show a preferred form 90 of guide-gripping member, this member taking the place of the cam 16 and the shoe 19.

The gripping member 32 is U-shaped in cross section and has a slot 33, (see Figure 6) for receiving the pin 17. The sides of 95 the member 32 are extended, and one side 34 is bent at right angles and is spaced from the end of the side 35. This provides an L-shaped space between the sides 34 and 35 for receiving a portion of the guide 3. 100

A spring 36 urges the gripping member 32 into an angular position so as to grip the guide 3 and prevent further movement of the shade 14 in an upward direction. In order to effect movement of the shade upwardly, the cord 25, secured to the member 32, is pulled, and this swings the member 32 into the horizontal position shown in Figure 6. The spring in the shade roller 13 is now strong enough to wind the shade and move 105 the tube 12 and associate parts upwardly. All of the other parts of the device forming the shade roller mounting are the same and therefore need no further description. The tube 11 is supported in adjusted position by 110 means of the gripping members 32, which take the place of the cams 16 and the shoes 19. 115

While I have shown only the preferred form of my invention, it should be understood that various changes or modifications may be made within the scope of the appended claims without departing from the spirit of the invention. 120

I claim:

1. In a shade roller and shade mounting, a tubular member, a cam pivotally carried by the member and having a cam edge, a guide, a shoe slidably in the guide and being pivoted to the cam and spring means for 130

causing the shoe and cam edge to grip the guide and prevent movement of the member along the guide in one direction.

2. In combination, a guide S-shaped in cross section, a shoe slidable along the guide and bearing against one side thereof, a cam pivoted to the shoe and having a cam edge bearing against the other side of the guide, a housing for a portion of the cam, said cam being pivotally mounted in the housing, and spring means mounted in the housing for causing the cam and shoe to grip the guide and prevent movement of the housing in one direction.

15 3. In combination, a pair of guides, a tubular member extending between the two, casings disposed in the ends of the member, cams pivotally carried by the casings, shoes pivotally secured to the cams and being slidable on the guides, guide rollers carried by the casings, said tube having an opening at its center, guide rollers disposed adjacent to the opening and being carried by the tube, and cords connected to the cams 20 and being passed around the rollers and out thru the opening.

4. In combination, a pair of guides each having a double channel, a tube extending between the guides, cams carried by the tube 25 and each being slidable in one of the channels, shade roller brackets carried by the tube and having wings slidable in the same channels as the cams, and guide-gripping shoes having portions slidable in both portions of each double channel.

5. In combination, a pair of guides S-shaped in cross section, a tube extending between the guides, guide-gripping members pivotally carried by the tube, spring means 40 for urging the members into gripping positions and manually-controlled means for moving the gripping members into released position.

6. In a device of the type described, a casting having a slot therein, a gripping member having a pin receivable in the slot, a free end of said member having a projecting portion and an angle shaped portion extending beyond the first-mentioned portion, a 45 guide received between the portions, spring means for moving the gripping member so that the portions will grip the guide and manually-controlled means for swinging the member into released position.

55 ROBERT SAA.
